CLOCK CASE

Rudolph M. Babel, Pawtucket, R. I., assignor to
General Electric Company, a corporation of
New York

Application August 11, 1951, Serial No. 16,241

Term of patent 14 years

(Cl. D42—7)

To all whom it may concern:

Be it known that I, Rudolph M. Babel, a citizen of the United States, residing at Pawtucket, in the county of Providence, State of Rhode Island, have invented a new, original, and ornamental Design for a Clock Case, of which the following is a specification, reference being had to the accompanying drawing, forming a part thereof.

In the drawing,

Fig. 1 is a front perspective view of a clock case, showing my new design;

Fig. 2 is a side elevational view in diagrammatic outline; and

Fig. 3 is a top plan view also in diagrammatic outline of the clock case.

I claim:

The ornamental design for a clock case, as shown.

RUDOLPH M. BABEL.
